UNITED STATES PATENT OFFICE.

CHARLES W. ANDREWS, OF DULUTH, MINNESOTA.

PRODUCTION OF CARBURETTED WATER GAS.

Application filed April 8, 1922. Serial No. 548,882.

This invention relates to gas production and more particularly to a new and improved method for the production of substantially nitrogen free gas from coal or similar fuels and to the enrichment of such gas.

In the production of gas from coal, as now generally carried out, the process of manufacture consists of two distinct steps. The first step involves the production of coke from the coal with the accompanying removal of gas, tar and ammonia. The second step involves the utilization of the coke so formed in manufacture of water gas, which may or may not be enriched or carburetted.

In the present practice, the first or coking operation is carried on in an ordinary retort which may be horizontal, inclined or vertical, or in some type of coke oven. The resulting coke is always more or less cooled in transferring it to a water gas generator with resultant loss of heat. A certain amount of the coke gasified in gas producers is consumed in heating the retorts or coke ovens although in the latter case a corresponding amount of coke oven gas is generally used in place of coke.

The formation of water gas in the gas generator is accomplished by alternately blasting or forcing air through the coke to bring it to a high temperature by means of combustion and then passing steam through the highly heated coke. During the blasting operation, blast gases are formed which are sometimes used to heat waste-heat boilers.

During the steaming operation, blue water gas is formed, the steam being broken down into hydrogen and oxygen, the latter uniting with the carbon of the coke to form carbon monoxide. If it is desired to enrich this blue water gas, it may be passed through a carburetter, where oil is added and then the oil and gas mixture may be passed through a superheater in order that the oil may be fixed so that it will remain in the gas and not condense out in cooling. The blast gases are utilized to heat the carburetter and superheater, and, as stated above, in some cases a waste-heat boiler.

This usual division of the gas-making process into two steps occasions very considerable heat losses due to the removal of the coke from the retorts or coke ovens and the

subsequent necessity of again raising its temperature in the gas generator. This process furthermore becomes costly on account of the expense in handling the coke including the loss in breakage; also the broken coke is not as efficient in the generator as the larger size coke. A further considerable heat loss occurs due to the fact that the water gas is formed at a relatively high temperature and that the sensible heat of the gas is not utilized.

A number of efforts have been made to completely gasify coal in a single continuous process. Nearly all such processes employ a vertical retort chamber surrounded by checkerwork and placed above a gas generator. In operation, fresh charges of coal are added periodically to the top of the retort. The air blast gases from the gas generator are passed through the checkerwork about the retort and serve to assist coking the coal therein.

During the periods when steam is introduced for the formation of the water gas, the outlet of the checker chamber is closed and the outlet at the top of the retort is opened. In this way, the blue water gas passes up through the retort and sweeps out the coal gas and tar from the coal and completes the coking. A superheater is sometimes added for the purpose of fixing enriching material which may have been added.

While this method offers a continuous process, it is, nevertheless, open to a number of objections. The efficiency is low owing to the fact that the heat of the blast gases is only partly utilized. Further, the production of ammonia in this process is very low. An additional objection lies in the fact that during the blasting period any gas, tar, and ammonia, which may be formed in the retort can only pass out by working down through the retort and going out with the blast gases.

Attempts have been made to produce gas continuously and with complete gasification of the fuel in a single unit by continuous blasting and steaming, but those systems necessarily produce a gas high in nitrogen and of correspondingly low heat value.

The object of my invention is to produce a substantially nitrogen-free gas continuously in one system with complete gasification of the fuel in the original generator

unit without transfer of the coke or carbonaceous residue and to subsequently enrich said gas and fix the enriching material.

An additional object is to increase the thermal efficiency of the gas-making process compared to that of present commercial methods. I accomplish this by using highly superheated steam and preheated air in the water gas generator, the temperature being such that both the steam and coke will be near the temperature of the water gas reaction, thus materially accelerating the reaction. The thermal efficiency is further increased by utilizing heat from the blue water gas and blast gases for fixing enriching material added.

It is also an object to provide a process which utilizes the heat of the blast gases not utilized in the water-gas generator for preheating the air and steam to increase correspondingly the temperature of the outgoing gases, both blast and blue, whereby the temperature of the blue gas will be sufficiently high to carbonize the fuel, as well as to fix any enriching material which may be added.

It is a further object to provide a process wherein the water gas generated is heated after its generation, the latter heating being preferably accomplished by passing the water gas through flues which have been heated by the blast gas.

It is an object to provide a process wherein the sensible heat of the water gas produced is utilized in the formation of coke, and wherein the water gas is further utilized to sweep out the coal gas and tar and ammonia from the coal, and wherein then the heat of the gas aids in fixing the tar and any other hydrocarbons which may be added.

It is another object to provide a process utilizing the sensible heat of superheated blue water gas to heat walls around retorts to the extent necessary to positively coke the exterior of the material in the retort, whereby sticking of the charge is minimized, and thereafter utilizing the remaining sensible heat in the gas to complete the coking of the fuel by passing directly through the fuel and at the same time on account of its volume sweeping out the gas, tar, and ammonia, at a lower temperature than would be the case if the fuel were heated from the outside.

Other and further objects will appear as the description proceeds.

The present application covers a process which is a modification of that disclosed in my application, Serial No. 542,342, filed March 9, 1922.

In its broad aspects, my invention involves the use of sufficient units so that coal is constantly being coked and water gas constantly being produced from coke. This permits a cyclic operation in such manner that each unit or each set of units serves in turn as a carbonizing chamber and then as

a water gas generator, both blasting and making gas.

In a preferable mode of operation, the installation involves three units operated in a cycle whereby throughout the cycle, one unit acts as a carbonizing chamber and the other two units serve as water gas generators, blasting and making gas in alternation, one or the other at all times making gas, the sensible heat of which gas is utilized in the unit serving as a carbonizing chamber. The blasting is limited in amount and duration to the heat requirements of the process, substantially no product of the blasting period being mixed with the nitrogen-free product of this gas generating process.

In order to preheat the air and steam under the best control and in the most efficient manner, I preferably use regenerative stoves in pairs, one stove for steam and the other for air, such pairs being adapted to be selectively associated with any of the gas generating units.

An important feature of the method lies in the fact that the retort portion is heated by the water gas so that substantially nitrogen-free gas is on both sides of the flue walls, that is, in the flues and in the retort thus preventing degradation should there be any leakage through the flue wall. It is therefore, possible to use any desired pressure or suction in handling the gas. During its period of blast, each unit is entirely cut off from the coking unit and during its period of making blue water gas, no blast gases are formed or passed through such unit.

A further important feature of the method is the use of a carburetter and superheater for cracking and fixing at the temperature best adapted for the purpose, the condensable vapors carried by the gas leaving the retorts, the heat for this being supplied either by admixture of hot blue water gas or from blast gases in the usual way.

A further important feature lies in the fact that a portion of the hot blue gas can be diverted from the retort and sent direct to the carburetter and superheater at a proper cracking temperature and there enriched by addition of tar or oil.

I have illustrated certain preferred embodiments of my invention in the accompanying drawings, in which—

Figure 1 is a somewhat diagrammatic plan view of an installation adapted for carrying out the process described herein;

Figure 2 is a vertical section taken on line 2—2 of Figure 1;

Figure 3 is a vertical section taken on line 3—3 of Figure 1;

Figure 4 is a horizontal section taken on line 4—4 of Figure 3;

Figure 5 is a horizontal section taken on line 5—5 of Figure 3; and

Figure 6 is a horizontal section taken on line 6-6 of Figure 4.

Referring now to Figures 1 and 2 of the drawings, the installation comprises three similar gas generating units A, B, and C. As shown in Figure 2, each unit comprises a lower section 11 which serves as a water gas generator. Each of these sections 11 has superposed thereon a coking retort section 12 which in the construction shown, comprises three separate retorts 13, 14 and 15. These retorts are surrounded and separated by brickwork carrying flues 16. A circular passage 17 is formed at the lower end of the retort section surrounding such section, which passage is provided with ports 18 leading to a chamber 19 located below the lower ends of the flues 16 and in communication therewith. The passage 17 is connected by suitable pipes 20 with the bustle pipe 21 which encircles the lower water gas section 11. This bustle pipe 21 has leading therefrom a plurality of pipes 22 which lead to tuyères 23 discharging into the water gas generator. The water gas generator, as shown, is provided with a grate bottom 24 and the pipes 25 and 26 lead into the ash pit below the grate bottom and are adapted for the introduction of air and steam, respectively.

In the typical installation as shown in Figures 1 and 2, three complete units similar to those just described are connected for joint operation. Flues 16 in each unit discharge into a space 27 at the top of the unit. The space 27 at the top of unit A is connected to the similar space at the top of unit B by means of passage 28 and a similar passage 29 connects the space 27 of unit B with the similar space 27 of unit C. The by-pass passage 30 connects the passages 28 and 29 and serves to directly connect the spaces 27 of units A and C. This passage 30 is controlled by valve 31 adjacent passage 28 and by valve 32 adjacent passage 29. The passage 33 leads from the passage 28 to the stove K. The passage 28 is controlled between unit A and passage 33 by means of valve 35 and between passage 33 and unit B by valve 36. The passage 33 is controlled by valve 37.

The stove K is connected by passage 38 with the stove L, the passage 38 being controlled by valve 39. A passage 40 leads from stove L to any heat recovery apparatus or to a stack of any usual type for discharge of spent gases, the passage 40 being controlled by valve 41.

The air main 41 is connected at 42 to stove L, the connection 42 being controlled by valve 43. The stove L is connected at 44 with the air header 45, the connection being controlled by valve 46. The header 45 connects to the bustle pipe 21 of unit A, the connection being controlled by valve 47, and

similarly connects to the bustle pipe of unit B, the connection being controlled by valve 48, and connects to the bustle pipe of unit C, the connection being controlled by valve 49.

The passage 50 leads from passage 29 to stove M, this passage 50 being controlled by valve 51. The passage 29 is controlled by the valve 52 between unit C and passage 50 and by valve 53 between unit B and passage 50. The stove M is connected to stove O by passage 54 which passage is controlled by valve 55. The stove O is connected to the air header 41, the connection being controlled by valve 34. The stove O is connected at 56 with the air header 45, the connection being controlled by valve 57. The stove O is further provided with the discharge passage 58 which leads to the heat apparatus or to the stack and which is controlled by valve 59.

The steam main 60 is connected at 61 to stove M, the connection being controlled by valve 62 and at 63 to stove K, the connection being controlled by valve 64. Stove K is connected to the steam header 65, the connection being controlled by valve 66, and stove M is similarly connected to the steam header, the connection being controlled by valve 67. The header 65 is connected at 68 to the bustle pipe 21 of unit A and is controlled adjacent said connection by valve 69. It is further connected to bustle pipe 21 of unit B at 70 and is controlled adjacent the junction by valve 71 and is connected to bustle pipe 21 of unit C at 72 and is controlled adjacent thereto by valve 73.

The passage 74 is located above the retort section of unit A and is provided with openings 75 communicating with the upper ends of the several separate retorts. This passage 74 leads to a common gas discharge passage 76 and is controlled before reaching said passage by valve 77. The passage 76 leads to an exhauster 85 which may be used to create a suction in the system. The unit B is provided with a similar passage 78 provided with openings 79 communicating with the retorts of the unit, the passage also joining the common gas discharge passage 76 and being controlled by valve 80. The unit C is similarly provided with the passage 81 communicating with the retort sections through openings 82 and controlled by valve 83 before its point of junction with the passage 76.

The passage 86 leads from the passage 28, to the carburetter and superheater 87, the passage 86 being controlled by valve 88. The passage 89 controlled by valve 90 connects the superheater with the discharge passage 74. The pipe 91, controlled by valve 92, leads into the carburetter 87. The passage 93 leads from the carburetter to the water seal box 94, and the discharge passage 95 from said box leads to the passage 76, be-

ing controlled by valve 96. The exhaust passage 97 leads from the carburetter to the stack 98, the passage being controlled by valve 99.

- 5 Similarly the passage 100 leads from the passage 29 to the carburetter and superheater 101, the passage 100 being controlled by valve 102. The passage 103, controlled by valve 104 connects the superheater with 10 the discharge passage 81. The pipe 105, controlled by valve 106, leads into the carburetter 101. The passage 107 leads from the carburetter to the water seal box 108, and the discharge passage 109 from said box 15 leads to the passage 76, being controlled by valve 110. The exhaust passage 111 leads from the carburetter to the stack 112, the passage being controlled by valve 113.
- 10 The passage 76 is controlled by valve 114 20 at a point between the junction of passages 74, 78 and 81 and the junction of passages 95 and 109 with the passage 76.

In the operation of my installation, it will be assumed, for the purpose of description, that unit A is filled to a point approximately two-thirds of the way up the retort section 12, with coke. Unit B is approximately completely filled with coke and unit C has its lower water gas generating 30 section 11 filled with coke and its upper retort section 12 filled with coal or similar fuel.

The units A and B are, in this portion of the cycle of operation, each utilized for the production of water gas. Unit A is 35 shown as on blast. The air for the blast is indicated in the drawing by a broken line consisting of dashes separated by two dots. This air comes through air main 41 and past valve 34 through the stove O into air 40 header 45 and past valve 47 into the bustle pipe 21 of unit A. It is to be understood, of course, that valves 55 and 59 of stove O are closed, and that valves 46, 48 and 49 of the air header are closed.

45 The bustle pipe 21 is connected by a pipe 20 to the passage 17 in the lower portion of the coke retort section and the valve 84 being open, a portion of the air passes through the pipe 20 into the passage. The main body of 50 the air passes from the bustle pipe through pipes 22 and is discharged through tuyères 55 23 into the hot coke in the water gas generator section. This air blast raises the temperature of the coke and the blast gases pass upwardly through the flue 16. The blast gases have been indicated in the drawing by a dash line.

In the chamber 19 the blast gases are joined by the secondary air which comes up 60 through the ports 18 from the passage 17. This secondary air joins with the blast gases to produce combustion in the flues, thus not only heating the coke in the retort sections but also heating the brickwork of the flues. 65 It is to be understood that the passage 74

is closed off by valve 77 and since the upper end of the retorts is blanked off, the blast gases do not pass up through the mass of coke in the retort. Supplemental air and steam may be introduced below the grate bottom 24 through pipes 25 and 26, respectively, if desired.

70 The blast gases pass from the flues 16 of unit A out through passage 28 and a portion goes to passage 33 and thence through stove 75 K and passage 38 to stove L and through passage 40 to any suitable apparatus for the further recovery of heat or to the stack. The valves 31 and 36 are closed to prevent passage of the blast gases to either units 80 B or C. Valves 43 and 64 are closed to prevent passage of the blast gases to the steam or air mains, respectively, from the stoves and valves 46 and 64 are closed to similarly prevent passage of the gas to the air and 85 steam headers.

The remainder of the blast gases go through passage 86, valve 88 being open, to superheater and carburetter 87 which they serve to heat. The gases then pass out passage 97 past valve 99 and out stack 98. Valves 90 and 96 remain closed so that none of the blast gases reach passages 74 and 76.

90 While unit A has been upon air blast, unit B has been making water gas. The steam 95 has been indicated in the drawing by a line comprising dashes separated by three dots. The steam has been introduced from main 100 60 through connection 61 past valve 62 into stove M where it has been superheated. It 105 thence passes through valve 67 to the steam header 65 and past valve 71 from the header to the bustle pipe 21 of unit B. It will be understood that the passages 50 and 54 leading from stove M, are closed by their 110 valves 51 and 55, respectively. The steam header is closed off from stove K by valve 66 and from the discharge pipes of units A and C by means of valves 69 and 73, respectively.

110 The steam passes from the bustle pipe 21 of unit B through the pipes 22 and tuyères 115 23 and is introduced into the highly heated coke contained within the water gas generator. Additional steam may be introduced, if desired, through pipe 26 under the grate 24 as shown. The steam is, preferably, substantially at the temperature of the water gas reaction and this reaction promptly takes place and water gas is evolved which 120 gas passes up through the flues 16. These flues have previously been heated by the passage of blast gases and this water gas, during its passage, has its heat very considerably increased.

125 It is to be understood that when on a steam run, the valve 84 controlling pipe 20 leading from the bustle pipe, is closed so that no steam enters the passage 17 of the retort section. The top of the retort sec- 130

tion is closed and also the passage 78 is closed by valve 80 so that the water gas does not tend to pass up through the coke in the retorts.

5 The water gas has been indicated in the drawings by the broken line consisting of alternate short and long dashes. The water gas passes up through flues 16 of unit B, thence through passage 29 to unit C and downwardly through the flues 16 of unit C. The retort sections of unit C are filled with coal or similar fuel and the sensible heat of the gas is largely absorbed in the walls of the passages 16 and thus serves to coke the coal in the retort. The water gas as it leaves the lower ends of the flues 16 is permitted to pass inwardly and upwardly through the mass of fuel in the retort and passes through openings 82 into passage 81. The valves 77, 20 and 80, as previously stated, are closed. It will be understood also that valves 32 and 51 are closed so that the water gas passes directly from unit B to unit C.

From passage 81, the water gas now carrying coal gas and condensable vapors, distilled from the coal in the retort of unit C, passes through passage 103 past valve 104 to the carburetter and superheater 101. The valve 114 is closed and prevents passage of the gas direct from passage 81 to passage 76. In the carburetter, tar, oil, or any suitable enriching material, may be added through pipe 105, valve 106 being opened for the purpose. From the carburetter 101 the carburetted gas passes through 107 to water seal 108 and thence through passage 109 to passage 76, the valve 110 being opened.

The units A and B are alternated on air blast and steam. Since the blast period is much shorter than the steam period, there will be certain periods when both units are making water gas. Their operation, however, will be so coordinated that there will be no periods when both units are on blast. Thus, heated water gas is constantly supplied to the unit C, where coking is taking place. When both units A and B are making gas, the valve 36 will be opened to permit the water gas to pass from flues 16 of unit A across unit B to unit C, or valves 31 and 32 may be opened to permit the gas to pass from unit A to unit C through passage 30. In the former case, valve 37 will be closed and in the latter case, valve 35. It will be readily apparent from the diagrammatic showing of Figure 1 that when unit B is on blast, its blast gases will be passed through stoves M and O and the unit will receive its air from stove L which has previously been heated from the blast gases from unit A. When unit A is on steam, it will receive its steam through stove K which it itself has heated during its blast period.

The operation of the units is preferably so coordinated that the coke in unit A will

have approximately been lowered two-thirds of the height of the coke retort section and the coke in unit B lowered approximately one-third of the height of the section at that time when the fresh fuel in unit C has been sufficiently coked. The operations in the several units are then changed for another period in the cycle of operation. Unit A is filled up with fresh fuel and units B and C now alternate on steam and air, passing their blue water gas through the flues of unit A to coke the material therein. It will thus be seen that the process is continuously carried on and at the end of another period of this cycle, the coke in unit B will be lowered two-thirds of the height of the retort section and that in unit C one-third of the height of the section, at which time the green fuel in unit A will have been coked. Unit B will then be filled up with fresh fuel and will take its turn as the coking unit of the installation.

It will be understood that in the method of operation so far described, the carburetters and superheaters 87 and 101 will be alternately heated by blast gases and then used to heat blue water gas and fix enriching material during at least a portion of the steam run. The enriching material may be tar or other material introduced directly into the carburetter or may be the coal gas and condensable vapors swept out of the coal in the coking retort section of a unit. In this method of operation, that portion of the water gas which is passed through the coking retort loses much of its heat in passing through the retort flues and the coal therein. Its greatest loss in this way occurs just after a step in the cycle when the fresh charge of coal is cold. During this period, some additional heat must be supplied in the carburetter if the enriching material is to be fixed. Later as the coal warms up, the heat lost by the water gas is less, and less or no heat is required to be supplied in the superheater.

Further during the first and cooler portion of the steam run, the volatile matter swept out is large and may be sufficient to constitute all the enriching material necessary so that none need be added in the superheater. Under some conditions, this material may be so great or of such a character that it is not desirable to fix it but to condense it, or part of it, out of the gas and the condensed material may be used for enriching a later portion of the run. During the later portion of the run, the volatile material swept out of the coal will be less and there will be no objection to adding enriching material in the carburetter.

In another modified method of operation, the necessary heat in the superheater may be supplied entirely by blue water gas and not by blast gases, or blast gases may be

utilized during a portion of a run and blue water gas during the remainder of the run. As has been fully described herein, the blue water gas in my apparatus may be generated at a temperature materially above that usual in the generation of such gas, by means of using preheated steam and air. Further, the blue water gas is heated in the flues of the unit in which it is generated so that the blue water gas contains considerable sensible heat which may be utilized for heating superheaters as well as, or instead of, for heating the coking retort of another unit. This heat may be utilized by sending part of the blue water gas through the coking retort of another unit, and sending the remainder through a superheater.

As has been stated, due to the fact that the blasting period is considerably less than the period of water gas production, there are considerable portions of working time when two units are both making water gas. During such periods, one unit may send its gas through the unit making coke and then one superheater while the other unit making gas will send its blue water gas directly to the other superheater which is thus heated by the hot blue water gas. As a variation of this method, some of the combined blue water gas output of the two units may be sent through the coking unit and one superheater while the remainder of the blue water gas goes direct to the other superheater.

As a further variation, some blue water gas may be sent to the same superheater to which the water gas from the coking retort is being sent in order to directly raise the temperature of such gas by mingling therewith.

Under some circumstances, due to variation in the rapidity of the several interdependent operations, due to differing conditions, materials or methods, it may be de-

sirable to add additional coke or coal to one or more of the units during different steps in the cycle of operations.

An important result of the method of operation whereby in the coking unit, one-third of the retort section remains filled with coke, when it is filled up with a fresh charge of coal, lies in a largely increased production of ammonia. Tests have shown that passing water gas through heated coke results in a very pronounced additional yield of ammonia over other methods, and my present method is adapted to accomplish this result.

It is to be understood that the apparatus shown is illustrative only and that my process is not limited thereto but may be carried out by various other means. It is my intention to cover all modifications and variations coming within the spirit and scope of the appended claim.

I claim:

The process of producing mixed carburetted water gas and coal gas, which comprises air-blasting carbonized residue to heat it, carrying off the blast gases through a heat absorbing structure surrounding a coking retort, passing steam into the heated residue to generate hot water gas, heating the water gas in the structure previously heated by the blast gases, passing the hot water gas through coal in a separate coking retort to coke and distil coal contained in said retort, adding enriching material to the mixed water gas and coal gas, and passing the mixture of gases through a suitable cracking and fixing chamber while said gases are at a proper temperature for the efficient cracking of the enriching medium and thereby carburetting the mixed gases.

Signed at Chicago, Illinois, this 28th day of March, 1922.

CHARLES W. ANDREWS.
